UNITED STATES PATENT OFFICE.

CHARLES F. WEBBER, OF BOSTON, MASSACHUSETTS.

SLEEVE-ADJUSTER.

SPECIFICATION forming part of Letters Patent No. 642,653, dated February 6, 1900.

Application filed November 6, 1899. Serial No. 736,045. (No model.)

To all whom it may concern:

Be it known that I, CHARLES F. WEBBER, a citizen of the United States, residing at Boston, in the county of Suffolk and State of Massachusetts, have invented an Improvement 5 in Sleeve-Adjusters, of which the following is a specification.

My invention has for its object to provide the sleeve of a shirt or similar garment with 10 a simple, cheap, and convenient device for adjusting its length as may be desired, either to better adapt it to the arm of the wearer or for the purpose of raising the cuffs to prevent them from becoming soiled.

15 To this end my invention consists in providing the sleeve of a shirt or similar garment with a pair of eyelet-holes arranged lengthwise of the sleeve at a suitable distance apart and combining therewith an independent detachable cord or tape looped through said eyelet-holes without being otherwise connected with the sleeve and provided with a clamping or fastening device whereby the length of the loop may be varied to adjust the length 25 of the sleeve, as hereinafter more fully set forth.

In the accompanying drawings, Figure 1 is 30 a view of a shirt having my improved sleeve-adjuster applied thereto, one of the sleeves being represented as being drawn up thereby. Fig. 2 is a longitudinal section of a portion of a sleeve, showing the manner in which the adjusting-cord is applied thereto. Fig. 3 is an enlarged view of the adjusting-cord and 35 its fastening device.

Referring to the drawings, A represents the body of a shirt or similar garment, and B B the sleeves thereof. Each of these sleeves is provided on the inner side or next to the 40 body, preferably above the elbow, with two eyelet-holes *aa*, arranged lengthwise of the sleeve at a suitable distance apart, preferably about three inches. Through these eyelet-holes is passed a loose or independent detachable cord or tape *b* with the free ends or portions extending outside, which are then brought together to form a loop, said portions being held together by a suitable clamping or fastening device, preferably a friction 45 clamping-hook *D*, secured to one end of the cord *b*. This hook is preferably composed of

spring metal bent to form a V-shaped opening, into which the opposite portion of the cord is drawn, as shown in Figs. 1 and 2, to cause it to be clamped tightly between the 55 two portions of the hook, the cord being thus held tightly without liability of slipping, and in this manner the length of the loop thus formed can be readily adjusted at will to vary the distance between the eyelet-holes *aa*, and 60 thus shorten or lengthen the sleeve, as may be desired by the wearer.

The cord or tape *b*, not being sewed or otherwise permanently attached to the sleeve, is intended to be removed therefrom before the 65 shirt is laundered, leaving the sleeve free from any attachments or additional parts which have rendered devices of this description as heretofore constructed objectionable.

The above-described sleeve-adjuster presents 70 many advantages over those hitherto in use, among which may be enumerated the following: It is exceedingly simple and inexpensive, occupies very little space, and its location above the elbow on the inner side of 75 the arm places it practically out of sight. The sleeve is not in any way injured by the eyelet-holes and is in condition for use either with or without the adjusting-cord. As the cord is readily removable, there is nothing 80 added to the sleeve that renders it any more difficult to launder with the attachment than without. The cost of the entire attachment is so trifling that it practically adds nothing to the cost of the shirt. The adjusting-cords 85 can be furnished at a very trifling expense and can be replaced in the sleeves at will by the wearer in a moment, as they are not sewed or otherwise permanently attached to the sleeves, as has hitherto been the case. When 90 applied to ready-made shirts, of which there is usually but one length of sleeve to a size, it affords a means for adapting the length of the sleeve to the arm of a customer who might not otherwise purchase the shirt on account 95 of the sleeves being too long.

What I claim as my invention, and desire to secure by Letters Patent, is—

The combination with the sleeve of a shirt or similar garment having eyelet-holes arranged lengthwise of the same, of a separate detachable cord or tape looped through said

eyelet-holes without being otherwise connected to the sleeve and free to move independently of the same, and provided at one end with a fastening or clamping device to engage 5 the free end, whereby the length of the loop may be varied to adjust or change the length of the sleeve, substantially as described.

Witness my hand this 3d day of November,
A. D. 1899.

CHARLES F. WEBBER.

In presence of—
P. E. TESCHEMACHER,
L. I. BASFORD.
